United States Patent Office

Des. 202,075
Patented Aug. 24, 1965

202,075

AUDIO-VISUAL APPARATUS

Henry C. La Paro, Parsippany, and Bernard Burkhoff,
Clark, N.J., assignors to International Telephone and
Telegraph Corporation, Nutley, N.J., a corporation of
Maryland

Filed Jan. 3, 1964, Ser. No. 78,064

Term of patent 14 years

(Cl. D61—1)

Fig. 2

Fig. 3

FIGURE 1 is a front perspective view of an audio-visual device, showing our new design;

FIGURE 2 is a top plan view thereof; and

FIGURE 3 is a side elevational view thereof.

The bottom and rear of the machine, not shown, are substantially plain and unornamented.

We claim:

The ornamental design for an audio-visual apparatus, as shown and described.
